UNITED STATES PATENT OFFICE

104,802

DESIGN FOR A VEHICLE BODY

Ralph F. Peo, Buffalo, N. Y.

Application October 24, 1936, Serial No. 65,476

Term of patent 7 years

To all whom it may concern:

Be it known that I, Ralph F. Peo, a citizen of the United States and a resident of the city of Buffalo, in the county of Erie and State of New York, have invented a new, original, and ornamental Design for a Vehicle Body, of which the following is the specification, reference being had to the accompanying drawing, forming a part thereof.

On the drawing:

Figure 1 shows an enlarged side elevational view of a fragmentary portion of a vehicle body showing my new design.

Figure 2 is a top plan view of the air conditioner casing shown in solid black lines in Figure 1.

Figure 3 shows a side elevational view of the complete vehicle body, and

Figure 4 is a top plan view thereof.

In the drawing, the portion illustrated in solid black lines constitutes the dominant feature of my design.

I claim:

The ornamental design for a vehicle body substantially as shown and described.

RALPH F. PEO.
